Primary Examiner — T. Chase Nelson*Assistant Examiner* — Mark Cavanna(74) *Attorney, Agent, or Firm* — Head, Johnson & Kachigian, P.C.(57) **CLAIM**

The ornamental design for a unity cross assembly, as shown and described.

DESCRIPTION

FIG. 1 is an assembled front perspective view of a unity cross assembly showing my new design;

FIG. 2 is a rear perspective view thereof;

FIG. 3 is a front view thereof;

FIG. 4 is a back view thereof;

FIG. 5 is a top view thereof;

FIG. 6 is a bottom view thereof; and,

FIG. 7 is a right side view thereof, the left side view being a mirror image thereof.

The dashed lines are included for the purpose of illustrating portions of the unity cross assembly that form no part of the claimed design.

1 Claim, 5 Drawing Sheets(56)
